UNITED STATES PATENT OFFICE.

FRANK J. FAIRCHILD, OF WYANDOTTE, MICHIGAN.

TROLLEY-CATCHER.

SPECIFICATION forming part of Letters Patent No. 657,342, dated September 4, 1900.

Application filed October 12, 1899. Serial No. 733,348. (No model.)

To all whom it may concern:

Be it known that I, FRANK J. FAIRCHILD, a citizen of the United States, residing at Wyandotte, county of Wayne, State of Michigan, have invented a certain new and useful Improvement in Trolley-Catchers; and I declare the following to be a full, clear, and exact description of the invention, such as will enable others skilled in the art to which it pertains to make and use the same, reference being had to the accompanying drawings, which form a part of this specification.

This invention relates to trolley-catchers, and has for its object an improved trolley-cord winder intended to be attached to trolley-cars, the object of which is to wind in the slack of the cord and prevent the sudden rising or flying up of the trolley-head should the trolley-wheel leave the wire. The attachment is intended to be placed at the rear of the car and is arranged to wind in and coil the slack of the trolley-line. It is arranged to allow the trolley-line to unwind from the reel that forms part of the attachment if it unwinds slowly, but to catch the reel and stop the unwinding of a cord from the reel if there is a sudden strain put upon it, such as is put upon a trolley-line when the trolley-wheel leaves the wire.

In the drawings, Figure 1 is an elevation. Fig. 2 is an elevation with the outer plate removed. Fig. 3 is a section through the ratchet and ratchet-wheel. Fig. 4 is an elevation of the drum. Fig. 5 is a vertical section longitudinal of the axis, taken at the line $x x$ of Fig. 3. Fig. 6 is a horizontal section and shows the hand-hole at the bottom of the case. Fig. 7 is a detail of the hook terminating the coiled spring.

A indicates the casing or barrel, which encloses the drum, the retrieving-spring, and the ratchet-wheel. This drum is provided with ears a , through which are bolt-holes for the bolts by which the attachment is secured to the car.

b indicates an adjusting-screw that extends through the casing of the drum, the object of which will be explained hereinafter.

c indicates the throat, through which the trolley-cord d leads into the drum.

e indicates the casing of an electric heater. The drum is mounted on an axle f . At the

end of the drum is a barrel g for a spring h . One end of the spring h is secured to the barrel and the other end terminates with a hook h' , that is adapted to catch in a notch in the axle f . This terminal hook is made by folding the end of the metal of the spring into three folds, so that said folds shall be against the recurved portion and against the shank portion of said hook, as shown in detail in Fig. 7. The threefold hook thus formed is less liable to break than a single-fold hook used in the same place.

On the inner side of the drum of the reel is a ratchet-wheel r , and on the casing is hung a pawl p . The pawl p is curved downward from the pin q , by which it is attached to the casing, and both ends are adapted to engage against the teeth of the ratchet. One end s extends toward the ratchet-teeth and is shaped to engage in notches between the teeth and prevent the revolution of the wheel and drum in the direction of revolution which the wheel has when the cord unwinds. The other end t of the pawl is adapted to drop into the notches between the teeth, but is not adapted to stop the revolution of the wheel, and this end t of the pawl is weighted or heavier than the other end, so that in its normal condition the pawl p rests with the end t on the surface of the ratchet-wheel. The end s rests out of engagement with the ratchet-wheel. If the cord be wound on the reel and the attempt be made to unwind it slowly therefrom, the end t of the pawl p will ride over the surface of the wheel, and the end s will not engage between the teeth because the pin q , on which the pawl swings, is far enough removed to allow both ends to just clear the teeth. If, however, a sudden jerk is given to the cord, the weighted end t of the pawl in rising over the high point of a tooth requires momentum enough to cause the end s to drop in front of a tooth, and the tooth itself then causes the end s to seat itself in the notch and stop the ratchet-wheel. A regulating-screw b projects from the outside through the case above the end s of the pawl. This regulating-screw determines the depth to which the end t sinks into the notches between the teeth, and consequently regulates the momentum given to the pawl by the rotation of the ratchet-wheel. The pawl must be regulated to allow the cord

to be drawn from the wheel at a convenient rate of speed when it is desired to allow the trolley-head to rise, and at the same time the regulation must be such that if the cord be drawn from the drum with the speed which it would ordinarily have when the trolley leaves the wire and the trolley-head springs upward then the pawl will be actuated and engage in the ratchet-wheel.

10 The under side of the casing is left open, as shown in Fig. 6. This is for the purpose of allowing rain or sleet to drop out from the casing and to allow access to the drum.

The spring *h* is of few coils, as it is only necessary to make it of such length as will allow the requisite motion of the trolley. Should it be desired at any time to wind up more of the cord than the spring will normally wind, this is done by turning the reel, 20 to which access may be had to the opening *k* in the bottom of the case, and whenever the reel is turned to wind the cord upon it the hook end *h'* of the spring slips around the axle or post, which the hook *h* normally engages.

25 The cord is preferably made in two pieces, one end of one piece being provided with a hook and the connecting end of the other piece being provided with a ring. If it be desired to separate the two, the cord is drawn from the reel until the connecting-fixture is outside the reel, the two parts are disconnected, and that part which is still on the reel is made fast, so that it will not fly back 30 into the drum. This connection is made when it is desired to swing the trolley, as in preparing to run a car backward. It is also made when it is desired to regulate the tension on the spring *h*.

35 40 On the side of the casing just below the the throat which leads through the casing is a housing *e*, in which is located any convenient form of electric heater, in which heater may be generated sufficient heat to melt ice and sleet if any should accidentally form on 45 the cord, and that part of the cord which is inside the drum will thus be kept dry and flexible, and if any of the cord which is ordinarily outside be wound into the drum while it is 50 wet or frozen it will soon become soft and pliable and dried.

The momentum required by the end of the pawl is not due to centrifugal force, but is the continuance of an absolute motion that 55 is begun by the end of the pawl, rising out

of an interdental notch and over the high part of the tooth, and this is a positive motion required immediately after the drum begins to revolve and one which produces the corresponding inward travel of the end *s* of the pawl before the ratchet has traveled to a space that equals in arc more than one or two of the teeth of the ratchet-wheel, and the consequent stoppage of the upward travel of the trolley when it jumps off the wire is very 60 promptly effected, and inasmuch as the trolley-wheel before leaving the wire must travel downward, and when it travels downward the spring winds in the cord, it will generally happen that the trolley will not rise as high 65 as the line-wire, but will stop below it.

What I claim is—

1. In a trolley-catcher, in combination with a reel and drum, a spring adapted to actuate the drum to wind the cord, a ratchet-wheel 75 connected with the drum, a detaining-pawl pivoted to the casing and normally out of engagement with the ratchet-wheel and provided with an end arranged to normally rest on the ratchet-wheel and to be actuated by 80 the revolution of the ratchet-wheel, means for yieldingly urging said end of said pawl toward said ratchet-wheel, and a set-screw, *b*, adapted to limit the movement of said end of said pawl toward the ratchet-wheel, substantially as and for the purpose described. 85

2. In a trolley-catcher, in combination with a winding-drum, a ratchet-wheel, a pawl arranged to be normally out of detaining engagement with the ratchet-wheel, but to be 90 actuated and thrown into detaining engagement therewith, and means for adjusting the pawl, substantially as described.

3. In a trolley-catcher, in combination with a reel and drum, a heating appliance, substantially as described. 95

4. The combination of a reel and drum, an axle *f*, having a notch therein, said reel and drum being pivoted upon said axle, a spring one end of which engages with said reel and drum, and having its other end folded upon itself and bent into a hook adapted to catch in the notch in said axle, substantially as shown and described. 100

In testimony whereof I sign this specification in the presence of two witnesses.

FRANK J. FAIRCHILD.
